MAX KRAUT, OF SAN FRANCISCO, CALIFORNIA

METHOD OF SELECTIVELY FLOATING ONE OR MORE MINERALS CONTAINED IN ORE
PULP

Application filed February 20, 1928. Serial No. 255,639.

The object and scope of the present invention pertains to the method of promoting and intensifying effects produced in that field of flotation process known as differential, preferential or selective flotation.

The usual method employed in present flotation to bring about the desired effects of selective flotation is the use of depressing or retarding reagents, which, added to a pulp containing a complexity of minerals, have the quality of selectively retarding or depressing one or more of these minerals without interfering with the free flotation of others.

15 As an example of such selective flotation may be cited the use of potassium cyanide in an alkaline ore pulp containing sulphide of lead, zinc and iron. The addition of these reagents causes a retarding of the flotation 20 of the iron and zinc minerals, without interfering with the flotation of the lead sulphide (galena) thus permitting the production of a high grade lead concentrate which, essentially free of zinc and iron, forms a commercially valuable product. Other retarding or depressing reagents used for this, or similar purposes, are sodium sulphide, potassium bichromate, sulphurous acid, etc.

25 By my improved process it has been discovered that this selective action or the retardation and depression effects mentioned can be realized without the use of such specific reagents as described, or where they are used the selectivity can be materially intensified, thus permitting a substantial reduction in the quantities of such reagents, thereby effecting important economies in the application of the process, and at the same time produce enhanced metallurgical results. 30 This peculiar selective effect or action I obtain by subjecting the pulp (prepared in the usual way) and containing a complexity of minerals to agitation and to the action of a partial vacuum, the intensity of which is controllable and at the same time introducing and working into the pulp mass a controlled and minimum quantity of air in a critical amount. Both the degree of vacuum and the 35 amount of air admitted are subject to varia-

tion depending on the ore and its constitute minerals.

By applying these principles in a large scale operation I have been able to obtain an excellent separation between the lead, zinc and iron minerals in ores generally, and particularly in an ore which had theretofore resisted all efforts at a successful separation by the normal methods referred to above.

An example of the results obtained on this ore before and after applying my present method will serve to illustrate the superiority of my present process.

Mill run after subjecting pulp to present well known methods universally in use:—

Mill head assayed 5% lead, 7% zinc, 6% iron.

Lead concentrates assayed 22% lead, 30% zinc.

No zinc concentrate was produced.

Flotation reagents used were for lead:—

Xanthate: 0.10 lbs. per ton.

Pine oil: 0.10 lbs. per ton.

Lime: 1 to 8 lbs. per ton.

Cyanide: 0.75 to 3 lbs. per ton.

No separation was effected.

Mill run after subjecting pulp to vacuum method:—

Mill heads, assayed 5% lead, 7% zinc, 6% iron.

Lead concentrates, assayed 65% lead, 5% zinc, 3% iron.

Zinc concentrates, assayed 2% lead, 55% zinc, 1% iron.

Flotation reagents used were for lead:—

Xanthate: 0.10 lbs. per ton.

Pine oil: 0.10 lbs. per ton.

Lime: 0.5 to 0.15 lbs. per ton.

Cyanide: 0.05 to 0.10 lbs. per ton.

Flotation reagents used for zinc were:—

Xanthate: 0.15 lbs. per ton.

Copper sulphate: 0.25 lbs. per ton.

An excellent separation and high grade lead and zinc products were obtained.

The preferred apparatus necessary to carry out my method, that is, to apply a controllable vacuum to the pulp mass simultaneously with a controlled admission of a quantity of air into said pulp mass, while the mass is in agitation is preferably constructed in the

following manner, reference being had to the accompanying drawings, wherein:—

Figure 1 is a transverse, vertical, sectional view of the preferred embodiment.

5 Figure 2 is a transverse, horizontal, sectional view on line 2—2 of Figure 1.

Figure 3 is a horizontal sectional view on line 3—3 of Figure 1.

10 The preferred form of construction, as illustrated in the drawings, comprises a substantially rectangular chamber 10, consisting of upper side and end wall sections 11, 12, 13 and 14, the lower portions 15, 16, 17 and 18 of the sections inclining towards the center 15 of the chamber 10, and a bottom wall 19, mounted upon a suitable supporting framework. Communicating with the bottom of the chamber 10 is an inlet pipe 20 through which the pulp to be treated is introduced 20 into the apparatus, the pipe 20 passing through the inclined portion 15 of wall section 11 and discharging into the chamber near the bottom open end 22 of a vertically disposed truncated conical shell or casing 23, suspended in the chamber 10 by the framework 23'. The upper portion of casing 23 terminates adjacent the upper edges of side walls 13 and 14 of chamber 10.

30 Disposed in casing 23 and rigidly secured to the lower portion of a vertically disposed shaft 26, is a hollow truncated cone 27, similar in configuration to the casing 23. Cone 27 is provided at its lower end with a sleeve 28 to which the shaft 26 is rigidly secured 35 and at its upper end it is provided with a frame 29 having a centrally disposed opening through which the shaft 26 passes. The upper end of shaft 26 passes through the bearing 31 secured to a cross beam 32 of the 40 supporting frame work, and on the upper end is secured a pulley 33, driven by a motor 33' through a belt connection.

45 The peripheral wall of rotating cone 27 is longitudinally slotted at 40 to permit air to be drawn therethrough to the space formed between shell 23 and rotor 27 during the operation of the apparatus.

50 The surface of the cone 27 is provided with a plurality of helical ribs 34 assisting the pulp flow in the interspace 34' between the shell 23 and cone 27.

55 Upwardly from the frame 29 extends an annular flange 41 having a running fit with a complementary flange 42 depending from the undersurface of a hood 43, carried by bearing sleeve 31. The peripheral edge 44 of the hood 43 depends into the chamber 10 to a point below the upper edge of the shell 23, and also below the upper edge of the outlet 45 controlled by a gate 46. The hood 43 forms a substantially air tight chamber 47, over the interspace between the shell 23 and cone 27, the chamber being sealed by the pulp level in the chamber 10. Complementary flanges 41 and 42 provide a chamber 48

at the upper end of the cone 27. An air inlet valve 49 is carried by the hood 43 and is manually controllable to admit air into the cone 27 and chamber 48, and a similar valve 50 is provided to control the admission of air 70 into chamber 47. Suitable ribs or fins 51 are carried on the inner surface of the skirt 44 of the hood 43 to prevent any swirling tendency of the pulp discharged into the chamber 47 by the action of cone 27. 75

In operation, the pulp enters the conical interspace 34' between the cone 27 and shell 23. In this space the action of the helices 34 rapidly elevates the pulp to be forcibly expanded, thereby causing the formation of a 80 partial vacuum in the pulp mass. The quantity of air which may be drawn into the pulp is controlled by valve 48 which permits a very fine adjustment of the air inlet to the interior of the rotating cone 27. This valve 85 controls both the quantity of air admitted and the degree of vacuum maintained in the rising column of the expanding pulp mass. Independent of this, the vacuum in chamber 47 is regulated by means of valve 50. The pulp on leaving the conical interspace 34' 90 enters chamber 47 where the pulp is brought to rest, being prevented from assuming a rotating action by projecting ribs 51, provided on the walls of said chamber for this purpose.

95 It must be noted that in operation, the pulp level in chamber 47 rises above the level of the tank, the height depending on the degree of vacuum maintained and controlled 100 by valve 50.

105 It will thus be apparent that in carrying out my method invention, I maintain the ore pulp either with or without a reagent added thereto, in a continuously moving body, and maintain the continuously moving body in vacuum by controlling the air admitted thereinto, and it is preferable that this continuously moving body be drawn from the main pulp body and again discharged there- 110 onto, the froth floating therefrom.

I claim:—

115 1. The method in the flotation process of floating selectively one or more minerals contained in ore pulp, which consists in subjecting a moving column of air-impregnated ore pulp to the action of a vacuum and proportioning the degree of vacuum and air entry into the pulp to selectively float one or more minerals from one or more other normally floatable minerals.

120 2. The method in the flotation process of floating selectively one or more minerals contained in ore pulp, which consists in inducing a flow of ore pulp along a defined path while introducing air thereinto and creating a vacuum within the ore pulp during said course of flow, and proportioning the degree of vacuum and air entry into the pulp to se- 125

lectively float one or more minerals from one or more other normally floatable minerals.

3. The method in the flotation process of floating selectively one or more minerals in ore pulp, which consists in inducing an agglomerate of ore pulp to flow in a continuous path, admitting air into said pulp and subjecting said pulp to interstitial vacuum produced therein by progressively increasing the cubic displacement of said agglomerate during an agitation thereof in the course of said flow, the degree of vacuum and air entry into the pulp being proportioned to selectively float one or more minerals from one or more other normally floatable minerals.

4. The method in the flotation process of floating selectively one or more minerals from one or more other normally floatable minerals contained in ore pulp, which consists in forming the pulp with its contained ores in a rising expanding column while admitting air thereinto in controlled quantities, and maintaining the rising expanding column in a degree of vacuum proportioned to the admitted air, the degree of vacuum being proportioned to selectively float one or more minerals from one or more other normally floatable minerals.

5. The method in the flotation process of floating selectively one or more minerals from one or more other normally floatable minerals contained in ore pulp, which consists in forming the pulp with its contained ores in a rising hollow column, increasing in diameter as it rises, introducing to said pulp controlled quantities of air, and maintaining the rising hollow column in a degree of vacuum, the degree of vacuum being proportioned to selectively float one or more minerals from one or more other normally floatable minerals.

6. The method in the flotation process of floating selectively one or more minerals from one or more other normally floatable minerals contained in ore pulp, which consists in continuously lifting from the main pulp body a rising column of the pulp containing ores, introducing into the pulp controlled quantities of air, maintaining the rising hollow column in a degree of vacuum proportioned to the quantity of air admitted to selectively float one or more minerals from one or more other normally floatable minerals, and discharging the column on to the main pulp body.

7. The method in the flotation process of floating selectively one or more minerals from one or more other floatable minerals contained in ore pulp, which consists in continuously removing from the main pulp body an expanding column of ore pulp, while admitting a partial air thereinto, maintaining the column in a partial vacuum, proportioning the degree of vacuum to selectively float

one or more minerals from one or more other normally floatable minerals.

8. The method in the flotation process of floating selectively one or more minerals contained in ore pulp, which consists in forming the pulp with its contained ores in a continuously moving column, and maintaining the moving column in a partial vacuum, and proportioning the degree of vacuum to selectively float one or more minerals from one or more other normally floatable minerals.

9. The method in the flotation process of floating selectively one or more minerals from one or more other normally floatable minerals in ore pulp, which consists in inducing an agglomerate of ore pulp to flow in a continuous path and subjecting said ore pulp to interstitial vacuum produced therein by forced expansion of the pulp agglomerate during said course of flow, and proportioning the degree of vacuum to selectively float one or more minerals from one or more other normally floatable minerals.

In testimony whereof I have signed my name to this specification.

MAX KRAUT.
